UNITED STATES PATENT OFFICE.

HENRY B. JOY, OF DETROIT, MICHIGAN, ASSIGNOR TO PACKARD MOTOR CAR COMPANY, OF DETROIT, MICHIGAN, A CORPORATION OF MICHIGAN.

DESIGN FOR A VEHICLE-BODY.

42,074.

Specification for Design.

Patented Jan. 2, 1912.

Application filed November 13, 1911. Serial No. 660,146. Term of patent 7 years.

To all whom it may concern:

Be it known that I, HENRY B. Joy, a citizen of the United States, residing at Detroit, in the county of Wayne and State of Michigan, have invented a new, original, and ornamental Design for a Vehicle-Body, of which the following is a specification, reference being had to the accompanying drawing, forming part thereof.

The figure is a side elevation of the vehicle body showing my design.

I claim:

The ornamental design for a vehicle body, as shown.

HENRY B. JOY.
